E. H. LOFTIN

CONTINUOUS INDUCTIVE TRAIN CONTROL SYSTEM FOR RAILROADS

Filed Dec. 5, 1925

UNITED STATES PATENT OFFICE.

EDWARD H. LOFTIN, OF NEW YORK, N. Y., ASSIGNOR TO GENERAL RAILWAY SIGNAL COMPANY, OF ROCHESTER, NEW YORK.

CONTINUOUS INDUCTIVE TRAIN-CONTROL SYSTEM FOR RAILROADS.

Application filed December 5, 1925. Serial No. 73,408.

This invention relates to automatic train control and more particularly concerns a receiving and amplifying system for train control systems of the continuous inductive type.

5 In train control systems of the well-known continuous inductive type, influences corresponding to traffic conditions are continuously transmitted from the trackway to a moving vehicle, the transmission of such influences being accomplished by means of electro-magnetic induction. An alternating current is usually supplied to the track rails or other suitable conductors along the trackway, and voltages are induced in suitable car-carried receiving circuits located in inductive relation to the trackway conductors. As the alternating currents used in the trackway conductors are preferably small, the air gap through which the electrical induction must 10 act necessarily large, and the voltages induced in the receiving circuits therefore comparatively small, it is necessary to provide suitable amplifying means for amplifying these voltages in order that the car-carried control apparatus may be operated in a reliable and satisfactory manner.

In the usual type of continuous inductive train control system, favorable traffic conditions ahead are usually indicated by the 15 transmission of control currents or impulses from the track rails to the vehicle, while these currents are cut off under unfavorable traffic conditions. It often occurs that alternating voltages are induced in the car-carried receiving apparatus of train control systems by reason of commercial alternating current power lines, or other sources of alternating current located in close proximity to the trackway. Undesirable alternating magnetic fields of this nature may also result 20 from the flow of large alternating propulsion currents in the track rails of electrified railway systems, the harmonics of the propulsion current being of the same order as the train control frequencies employed. These stray currents or magnetic fields frequently result in a false operation of the car-carried apparatus, causing a clear indication or operation of the car-carried devices under unfavorable traffic conditions, or some other

dangerous and undesirable effect. As these stray alternating currents have a different frequency from the current employed to transmit the train control impulses, it is desirable and in fact essential to the reliable 55 operation of a train control system of this type, that the receiving and control devices be responsive to the train control frequency only. It is evident that the receiving equipment must be very selective, as in the case of 60 a railroad employing alternating propulsion currents the receiving equipment must respond to the weak current of train control frequency while large currents of propulsion frequency are flowing in the track rails. 65

With the above and other considerations in mind, it is proposed in accordance with the present invention to provide receiving and control apparatus for automatic train control systems which is sensitive to the weak 70 induced voltages received from the trackway, which is highly selective in that it responds to the train control frequency only, and which is simple, compact and inexpensive as compared to the amplifying systems heretofore employed. More specifically, it is proposed to provide an amplifying system for 75 train control employing a lightly-loaded mechanically resonant relay together with means for making available the energy supplied by such relay.

Other objects, advantages and characteristic features of the invention will become apparent as the description thereof progresses. 85

In describing the invention in detail, reference will be made to the accompanying drawing in which a single figure has been shown, representing in a diagrammatic manner, a simple train control system of the continuous 90 inductive type provided with an amplifying system embodying the present invention.

The system of the present invention has been shown applied to a very simple continuous inductive train control system of the 95 two-position type, it being understood that the receiving equipment is equally applicable to many other types of inductive train control.

The trackway apparatus shown is of the 100

type well-known in the art, and requires but little explanation to those familiar with railway signaling and train control practice. Track rails 1 are divided into blocks by the insulating joints 2, the block I and the adjacent ends of the blocks H and J having been shown. The corresponding devices in the several blocks have been represented by like reference characters having distinctive 10 exponents. Suitable track relays 3 are connected across the track rails at the entrance end of each block as shown, these relays being normally energized by current from the track batteries 4 connected across the track 15 rails at the exit end of each block. Alternating train control current of a suitable frequency is applied to the two track rails in series by the transformer 5 connected in series with the track battery 4 across the 20 track rails at the exit end of each block, the primary winding of this transformer being energized from the transmission line 6 through the contacts 7 and 8 of the track relay 3 of the first block in advance. It is 25 evident that the presence of a train in a given block, say the block J, shunts the track circuit and train control currents from the track rails behind the train in that block, causing the de-energization of the track relay 3¹ at the entrance end of the block. The 30 de-energization of this track relay 3¹ causes the train control current to be cut off from the track rails of the first block I in the rear of the occupied block by opening the energizing circuit for the transformer 5 at the contacts 7¹ and 8¹ of the relay 3¹.

As wayside signals are sometimes used in connection with a train control system of this type, the wayside signals Z, which may be of the color light, semaphore or other suitable type, have been shown at the entrance end of each block. The well known circuits and devices for operating these wayside signals have not been shown, as this apparatus is well known to those skilled in the art and forms no part of the present invention.

A railway vehicle has been conventionally represented in the block H by the wheels and axles 10. This vehicle is provided with receiving coils 11 arranged in front of the leading axle of the vehicle and in inductive relation to the track rails 1. The receiving coils 11, which may or may not be provided with laminated iron cores, are so connected that voltages induced therein by alternating currents flowing in opposite directions in the two track rails, will be additive.

The circuit through the receiving coils is preferably tuned to resonance at the train control frequency by means of the condenser 12, and is connected as shown in series with the winding 13 of a tuned resonant relay R. The relay R may take any suitable form, and as shown comprises a laminated core 14 of

general U-shape, having a suitable winding 13 on the back yoke thereof. A tongue or armature 15 is rigidly fixed to one leg of the core 14, and extends over the other leg to leave a small air gap in the magnetic circuit 70 as shown, the armature 15 being preferably made of some flexible resilient material and being biased to the raised position as shown. The tongue 15 is so designed, constructed, and mounted, as to have a periodicity or 75 natural period of vibration equal to the frequency of the train control current. A vibrating reed or contact member 16 is soldered or otherwise suitably secured to the tongue 15, the reed 16 being designed to have 80 the same natural period of vibration as the tongue. The reed 16 is preferably mounted at some distance from the free end of the tongue 15, as with this arrangement the mechanical coupling between the reed and the tongue is loose, and the two elements do 85 not have much tendency to vibrate at two different frequencies as would be the case if the reed 16 were mounted at the end of the tongue 15. An adjustable contact screw 17 90 is mounted in such a manner as to make a light contact with the reed 16 at the extreme end of the stroke of the reed when the relay is vibrated at the frequency to which it is mechanically tuned. This arrangement of 95 the contact engagement insures that the load on the relay is very light and that the interference of the loading to the resonant tuning of the moving parts is a minimum.

As the current carrying capacity of the 100 contacts 16 and 17 of the relay R is necessarily limited, special apparatus must be provided to make this current available for controlling the car-carried apparatus. In the present embodiment, this apparatus takes 105 the form of a three-element vacuum tube 18 of the well known type. The vacuum tube 18 is provided with the usual filament 19, grid 20 and plate 21, the usual filament heating battery 22 in series with a filament resistance 23 being provided as shown. The contacts 16 and 17 of the relay R are connected in series with the grid circuit of the tube 18 through a resistance unit 24, a portion 110 of the plate battery 25 being included in this circuit, as shown. In order that the plate circuit of the tube 18 may carry a minimum amount of current when the contacts 16 and 17 are open, a suitable source 115 of potential comprising the battery 29 is included in parallel with the grid circuit to place a negative potential bias on the grid, a resistance unit 26 being placed in series 120 with this battery to prevent an excessive flow of current through the contacts 16 and 17 when these contacts are closed. The output circuit of the vacuum tube 18 is connected to a suitable sensitive relay 27, responsive to unidirectional currents.

Any suitable form of train control appa- 130

ratus may be used to control the vehicle 65 brakes, cab signals or the application of power. As the particular control system used forms no part of the present invention, and as the initiation of such car-carried systems to give a restrictive control is usually 70 accomplished by the de-energization of an electro-magnetic device, the train control device TC has been shown, it being assumed 75 that the de-energization of this device acts in some suitable manner to give a restrictive automatic control.

Operation.

15 In the drawing, the system has been shown in its normal operating condition, that is, with a train proceeding under clear traffic conditions ahead with all circuits and devices properly energized. For convenience, 20 the letters B and C have been used to designate the opposite poles of a suitable source of energy, preferably a storage battery.

Considering first the operation of the system of the present invention under clear 25 traffic conditions, assume that a train equipped with the apparatus shown is traveling in a clear block, that is, with no other train in the first two blocks in advance thereof. Under these conditions, alternating current 30 of train control frequency flows in the track rails in advance of the train and induces corresponding voltages in the receiving coils 11. This voltage is impressed on the winding 13 of the relay R through a circuit which 35 is obvious from the drawings, and the tongue or armature 15 together with the reed 16 are caused to vibrate at train control frequency, the reed 16 engaging the adjustable contact 17 at the extremity of each 40 stroke. It should be noted that by reason of the electrical and mechanical tuning, voltages of other than train control frequency do not cause the tongue 15 and the reed 16 to vibrate at as great an amplitude 45 as do the voltages of train control frequency, and for this reason stray currents or magnetic fields do not effect the proper operation of the car-carried apparatus.

The engagement of the reed 16 with the 50 adjustable contact 17 impresses a positive voltage on the grid 20 of the vacuum tube 18 through a circuit which may be traced as follows: from the filament 19, wires 30, 31 and 32, negative terminal of the plate battery 25, an intermediate positive point of the battery 25, through the wire 33, resistance unit 24, wire 34, stationary contact 17, reed 16 and armature 15 of the relay R, wires 35 and 36 to the grid 20. A negative 55 potential bias is maintained on the grid 20 by the battery 29 through a circuit which is obvious from the drawings, thereby preventing the flow of any appreciable current in the plate circuit of the tube when the con-

tacts 16 and 17 are open. The resistance 65 units 24 and 26 prevent the short circuit of the batteries 25 and 29, when the contacts 16 and 17 are closed, thus avoiding any undesirable arcing at the contacts which would cause these parts to pit and corrode and would rapidly change the mechanical tuning 70 of the relay R.

The positive voltage impressed on the grid 20 causes the flow of an appreciably pulsating current in the plate circuit, which 75 current serves to energize the relay 27, this relay having sufficient inertia, or being otherwise made slightly slow acting, through a circuit which may be traced as follows: from the relay 27, wire 38, plate battery 25, 80 wires 32, 31 and 30, filament 19 of the tube 18, plate 21 and wire 39 to the relay 27. The energization of the relay 27 causes the 85 energization of the train control device TC through a circuit which is obvious from the drawings, and the train proceeds in the clear block without automatic restriction.

If the train under consideration enters a 90 caution block, that is, the first block in the rear of an occupied block, no train control current flows in the track rails and the relay R is not energized to close its contacts 16 and 17. Under these conditions, the grid 20 of the tube 18 is maintained at a negative potential with respect to the filament 19, and 95 practically no current flows in the plate circuit of the tube. The relay 27 is therefore de-energized, causing the de-energization of the train control device TC, and an automatic brake application or other restrictive 100 control is imposed.

As the train under consideration proceeds 105 through the caution block and enters a danger or occupied block, the train control current is shunted from the track rails by the train in advance, and the relays R and 110 27 and the train control device TC remain de-energized. The train under consideration, therefore, continues under restrictive control in the occupied block.

From the description given, it is evident 115 that a highly selective and sensitive receiving system for automatic train control systems has been devised. It should be particularly noted that, due to the mechanical tuning of the relay R, the contacts 16 and 17 thereof are closed only when a voltage of the proper frequency is induced in the receiving coils 11. It should also be observed that very appreciable pulsations in 120 the plate circuit current of the tube 18 may be obtained, as the grid voltage may be varied from a normal negative bias of say 30 or 40 volts to a positive bias, when the contacts 16 and 17 are closed, of 30 or 40 volts, thus providing a voltage variation of the grid of from 60 to 80 volts. This large variation in grid potential insures that suffi-

cient current flows in the plate circuit of the tube to energize the relay 27 under clear traffic conditions.

Although the system of the present invention has been described in a rather specific manner, and in connection with one specific form of train control system only, it should be clearly understood that the invention is capable of certain modifications, changes 10 and combinations and that its scope is limited only as indicated by the appended claims.

What it is desired to secure by Letters Patent, is:—

1. In an automatic train control system, a trackway means for carrying an alternating current of a predetermined frequency, a vehicle carried receiving circuit adapted to be excited by the field of said trackway 20 alternating current, a relay in said receiving circuit having two vibratory elements, each of said elements having a mechanical periodicity equal to said predetermined frequency and one of said elements deriving 25 its energy for vibration from the other, and train control means controlled by said vibratory elements.

2. In an automatic train control system, trackway circuits energized by an alternating current of a predetermined frequency, a car-carried receiving circuit adapted to be energized by said alternating current, a relay connected in said receiving circuit and having a vibratory contact element mechanically tuned to resonance at said predetermined frequency, an amplifier having an input circuit and an output circuit, a source of energy, means whereby said vibratory contact of said relay connects said source of 40 energy to said input circuit, and train control means controlled by said output circuit.

3. In an automatic train control system, in combination with trackway means for inductively transmitting alternating voltages of a predetermined frequency to a moving vehicle, car-carried apparatus comprising a receiving circuit, a relay in said receiving circuit, a vibratory armature on said relay having a mechanical periodicity equal to 45 said predetermined frequency, a three-element vacuum tube having a grid circuit, means for normally fixing the potential of said grid circuit and means whereby the potential of said grid circuit is varied in accordance with the vibrations of said vibratory armature.

4. In an automatic train control system, in combination with trackway means for inductively transmitting alternating voltages 60 of a predetermined frequency to a moving vehicle, car-carried apparatus comprising a receiving circuit, a relay in said receiving circuit having a vibratory armature mechanically tuned to resonate at said predetermined frequency, a three-element vac-

uum tube having a grid circuit and a plate circuit, means for applying a source of potential to said grid circuit in accordance with the vibrations of said vibratory armature and an electro-responsive control device 70 connected in said plate circuit.

5. In an automatic train control system, in combination with trackway means for inductively transmitting alternating voltages of a predetermined frequency to a moving 75 vehicle, car-carried apparatus comprising a receiving circuit, a relay connected in said receiving circuit and having a vibratory armature, a vibratory contact reed secured to said armature, said reed and said armature being mechanically tuned to have a periodicity equal to said predetermined frequency, a stationary contact arranged to be lightly engaged by said contact reed when said reed and said armature are vibrating 80 at said predetermined frequency, a source of potential connected in series with said stationary contact and said contact reed, and a potential operated amplifying device having an input circuit connected with said source 85 of potential and said contacts.

6. In an automatic train control system, in combination with trackway means for inductively transmitting alternating voltages of a predetermined frequency to a moving 95 vehicle, car-carried apparatus comprising a receiving circuit electrically tuned to resonate at said predetermined frequency, a relay connected in said receiving circuit and having a vibratory armature, a vibratory contact reed secured to said armature, said reed and said armature having a vibratory periodicity equal to said predetermined frequency, an adjustable stationary contact arranged to be lightly engaged by said contact 100 reed at the extremity of each vibration thereof, a three-element vacuum tube having a grid normally biased to a negative potential and a plate circuit responsive to variations of grid potential, and a source of potential controlled by the engagement of said reed and said stationary contact to apply a positive potential to said grid, and a train control device controlled by said plate circuit. 110

7. In an automatic train control system, in combination with trackway means for transmitting electrical impulses of a predetermined periodicity to a vehicle, vehicle carried apparatus comprising a receiving circuit electrically tuned to resonate at said periodicity, an electro-mechanical device in said circuit having a plurality of movable parts each mechanically tuned to resonate at said predetermined frequency, an amplifier of the vacuum tube type having its input circuit controlled by said movable parts, and train control means controlled by said amplifying device. 125

8. In an automatic train control system, 130

a trackway means for carrying an alternating current of a predetermined frequency, a vehicle carried receiving circuit adapted to be excited by the field of said trackway alternating current, a relay in said receiving circuit having two vibratory elements, each of said elements having a mechanical periodicity equal to said predetermined frequency and one of said elements being vibratory superimposed at an intermediate point 10 in the other, and vehicle control means controlled by said vibratory elements.

In testimony whereof I affix my signature.

EDWARD H. LOFTIN
